VARIABLE SPEED MECHANISM.

APPLICATION FILED FEB. 2, 1903.

NO MODEL.

UNITED STATES PATENT OFFICE.

HENRY MCCOY NORRIS, OF CINCINNATI, OHIO.

VARIABLE-SPEED MECHANISM.

SPECIFICATION forming part of Letters Patent No. 726,976, dated May 5, 1903.

Application filed February 2, 1903; Serial No. 141,400. (No model.)

To all whom it may concern:

Be it known that I, HENRY MCCOY NORRIS, a citizen of the United States, residing at Cincinnati, in the county of Hamilton and State of Ohio, have invented certain new and useful Improvements in Variable-Speed Mechanism, of which the following is a specification.

My invention relates to the production of a speed-variator.

10 The prime object of this invention is to produce four changes of speed from a comparatively small number of gear-wheels.

While I have shown my improvement as an individual mechanism, it is primarily adapted and intended to be incorporated into a machine-tool organization, preferably as the primary speed-changing element between the counter-shaft and the spindle or first work-shaft of the tool, whether a lathe, drill, milling-machine, or a planer. Thus it constitutes a very acceptable substitute for the ponderous and objectionable cone-pulley system; but the improvement has other uses. It may be used as an independent speed-variator, a counter-shaft attachment, or it may be incorporated at some other position in a machine-tool organization than that first mentioned. For instance, in that class of engine-lathes employing a cone of gear-wheels and a tumbler with its pinion and driving gear-wheels my improvement may be used as a compounder therefor. Being essentially a speed-variator, the functions of this device as a means for compounding one or more other speed-changing systems of a train is equally useful and desirable.

The features of my invention are more fully set forth in the description of the accompanying drawings, forming a part of this specification, in which—

Figure 1 is a central vertical section of my improvement. Fig. 2 is a section on line xx , Fig. 1.

A represents a suitable housing, frame, or support having journal-bearings $a a' b b' c c'$, within which journals are mounted, respectively, the driving-shaft B, the intermediate C, and the driven or work shaft D.

E represents the driving pulley-wheel on shaft B. The connection between the work-shaft D and any further working elements is not shown. Within the housing A and mount-

ed loosely upon the shaft B are the gear-wheels 1 and 2, having the clutch members $d d'$ on their opposing faces.

F represents a clutch slidable on shaft B between the gear-wheels 1 and 2, adapted to engage into either of the clutch members $d d'$, whereby either of said gear-wheels 1 and 2 may be fixed to turn with said shaft B.

Upon the work-shaft D are the loose gear-wheels 6 7, having the clutch members $f f'$ upon their opposing faces adapted to be engaged by the sliding clutch G, mounted on shaft D between them. The clutches are of the ordinary form of friction-clutches in which a friction-ring is employed, said ring being compressed within the gears, whereby any one of the four loose gear-wheels are clutched to their respective shaft by the clutches F and G.

3 represents a gear-wheel on shaft C, connecting in train gear-wheels 1 and 6.

4 5 represent compound gear-wheels on shaft C, gear-wheel 5 being intermeshed with gear-wheel 2, and gear-wheel 4 being intermeshed with gear-wheel 7.

Preferably gear-wheels 1, 4, and 6 are of equal diameter and gear-wheels 2 and 5 for the purpose of multiplying or reducing the speed in a given ratio. Obviously, however, this ratio is one of numerical selection, dependent upon the particular requirements of the speed-changer for a given work.

The clutch F is connected to a yoke-arm H, and clutch G is similarly connected to the yoke-arm I. These yoke-arms preferably project outwardly toward the front of the machine and are provided with the ears J J' at their outer end.

K represents a rod journaled in the lugs g , inwardly projected from the side of the casing, this rod K passing through the ears J J' of the yoke-arms H I. The yoke-arm I is secured to the said rod K, so as to turn therewith, the means shown being a set-screw h through the ear J'. At the upper end the rod K passes loosely through the ear J, forming a fulcrum therefor.

L represents a lever cast integral with the ear J of the yoke-arm H, and M represents a lever attached to the rod K, as shown, by means of a set-screw.

Lever L, controlling the clutch on shaft B,

fulerums on rod K. Lever M, controlling the clutch on shaft D, is secured to rod K, which fulerums in the casing-lugs $g\ g'$.

Mode of operation: As shown, gears 2 and 5 are even, and gears 3 and 7 are twice the diameter of gears 1, 4, and 6. If the lever L be moved to throw the clutch F into clutch member d' and the lever M be moved to throw the clutch G into the clutch member f' , gear-wheels 1 and 6 will be fixed to their respective shafts, and hence the shaft D will be driven at an equal speed with shaft B. The lever L remaining in this last-named position, if the lever M is shifted in the opposite direction remaining gear-wheel 7 will be clutched to shaft D, shaft D being driven through the train of gears 1, 3, 4, and 7 at a speed one-fourth as great as the speed of shaft B. The lever M remaining in the last-named adjusted position, if the lever L is now shifted in the other direction remaining gear-wheel 2 will be clutched to shaft B, and shaft D will be driven through the train of gear-wheels 2, 5, 4, and 7 at one-half the speed of shaft B. The lever L remaining in this last-named adjusted position, if now the lever M be shifted in the opposite position the remaining gear-wheel 6 will be clutched to shaft D, and shaft D will be driven through the train of gear-wheels 2, 5, 3, and 6 at a speed twice as great as the speed of the shaft D. By this construction four speed changes are obtained from seven gear-wheels.

Having described my invention, I claim—

35 1. A speed-variator comprising a casing, three parallel shafts journaled therein, different-diameter gear-wheels loose on the first shaft, means for rotating said first shaft, means on said first shaft for clutching either 40 of said loose gear-wheels thereto, two gear-wheels loosely mounted on the third shaft, means on said third shaft for clutching either of said loose gear-wheels thereto, an intermediate gear-wheel on the second shaft connecting in train two of the opposing gear-wheels on the first and third shafts, a compound intermediate gear-wheel on the second shaft, one of the members of which intermeshes 45 with the remaining gear-wheel on the first shaft, the other member intermeshing with the remaining gear-wheel on the third shaft, and means for shifting said clutches, substantially as described.

2. A speed-variator comprising a casing, three parallel shafts journaled therein, two gear-wheels loose on the first, and two gear-wheels loose on the third shafts, clutches on said shafts between the respective gear-wheels thereon, two of the gear-wheels on said 55 shafts being disposed in the same plane, the remaining two gear-wheels being disposed in parallel planes, a simple intermediate gear-wheel on the second shaft connecting in train two oppositely-disposed gear-wheels on the 60 first and third shafts, a compound intermediate gear-wheel on the second shaft connecting 65

in train the two-gear-wheels disposed in parallel planes on said shafts, and means for shifting said clutches, substantially as described.

3. A speed-variator, comprising a casing, 70 three parallel shafts journaled therein, means for rotating the first shaft, two different-diametered gear-wheels loose on the first shaft, a sliding clutch between them, two different-diametered gear-wheels loose on the third shaft, a sliding-clutch between them, two of said four gear-wheels being disposed in the same plane and two being disposed in parallel planes, an intermediate gear-wheel on the second shaft connecting the gears of the same 75 plane, compound intermediate gear-wheels on the second shaft connecting the gear-wheels of parallel planes, each clutch having a shifting-arm, a rod journaled in the casing to engage one of said clutch-arms loosely and the other of the clutch-arms fixedly, and levers attached respectively to the clutch-arms, one fulcrumed on said rod, and one fixed to said rod, for independently shifting the clutches, substantially as described. 90

4. A speed-variator comprising a casing, three parallel shafts journaled therein, two gear-wheels loose on the first and two gear-wheels loose on the third shafts, the gear-wheels on each shaft being relatively of larger 95 and smaller diameter, two of the gear-wheels on the first and third shafts being of the same diameter for an equal drive, two of said four gear-wheels being in the same plane and two being in parallel planes, clutches on said 100 shafts between said gear-wheels, means for shifting the same, a simple and a compound intermediate gear-wheel on the second shaft, connecting said driving and driven gear-wheels in four different trains through the 105 shifting of the clutches, substantially as described.

5. In a speed-variator, a casing, three parallel shafts journaled therein, clutches on the driving and driven shafts, a series of seven 110 gear-wheels arranged on said shafts, in the relation of driving, intermediate and driven gear-wheels, and means for shifting said 115 clutches, whereby said shafts may be connected through said gear-wheels in any one of four 120 separate trains, substantially as described.

6. A speed-variator comprising a set of seven gears of varying ratios arranged in series on three shafts, a driving, an intermediate and a driven shaft, clutch-and-lever mechanism on said driven and driving shafts, and so disposed as to clutch any one of said gears on said driving and driven shafts, through which four changes of speed may be obtained by varying manipulations of the clutches, substantially as described. 125

In testimony whereof I have hereunto set my hand.

HENRY MCCOY NORRIS.
